UNITED STATES PATENT OFFICE.

HERMANN PLAUSON, OF HAMBURG, GERMANY.

PROCESS FOR THE MANUFACTURE OF HEXAMETHYLENE TETRAMINE.

1,408,826.

Specification of Letters Patent. Patented Mar. 7, 1922.

No Drawing.

Application filed February 12, 1921. Serial No. 444,489.

To all whom it may concern:

Be it known that I, HERMANN PLAUSON, Esthonian subject, residing at Hamburg, Germany, have invented certain new and 5 useful Processes for the Manufacture of Hexamethylene Tetramine, (for which I have filed an application in Germany Sept. 9, 1919,) of which the following is a specification.

10 It is known that on passing a mixture of methane with oxygen or air over heated contact substances, formaldehyde and other substances are formed. But the yield was always too small for practical purposes since 15 in all processes depending on this principle the formaldehyde first formed again decomposed for the most part. The reason for this appears to be that the oxygen acted too energetically on the readily oxidizable aldehyde so that high oxidation products are 20 produced at once. Frequently the main cause of the difficulty is that the formaldehyde cannot exist under the conditions under which it is formed so that it is again decomposed into its elements through the high 25 temperature in the reaction zones.

Now it has been found that it is possible to perform the reaction in a new way, viz. in presence of ammonia gas which at once 30 forms a more stable compound, hexamethylene tetramine, with the first-formed formaldehyde under certain conditions so that the formaldehyde is saved from destruction and can be obtained in a technically satis- 35 factory yield.

It has hitherto been proposed to oxidize methane in presence of steam or of a liquid solvent for the formaldehyde which is formed. It has been found however that in 40 the action of air or oxygen on methane in presence of ammonia gas, the simultaneous presence of steam only exerts a disturbing action. The observation has been made and confirmed by numerous analyses that the 45 presence of fairly large quantities of hydrogen vapour always leads to the formation of water at the expense of formaldehyde while carbon monoxide and carbon dioxide or ammonium carbonate is also 50 formed.

Although it is known that acetaldehyde-ammonia is formed by passing acetylene and ammonia over a heater catalyst, it could not

have been deduced that hexamethylene-tetramine could be produced in good yield 55 by oxidation of methane in presence of ammonia gas and air under certain conditions because firstly the behaviour of an unsaturated hydrocarbon containing a triple linkage such as acetylene is very different from that 60 of a saturated hydrocarbon such as methane and secondly it is well known that the formation of acetaldehyde occurs more easily than that of formaldehyde. Hence it could not have been foreseen that the presence of 65 ammonia would so considerably raise the yield of formaldehyde or hexamethylene tetramine as an intermediate product.

Such an assumption in fact is opposed to the researches of Löb (Zeitschrift fur 70 Elektro-Chemie Vol. 18 page 850) according to which the formation of hexamethylenetetramine, under the influence of electric current does not take place essentially faster than the decomposition of formaldehyde. Furthermore the experimental conditions 75 are very different from those according to the present invention.

If the apparatus is so chosen that the reaction gases are heated for a very short 80 time to a high temperature, the chemical combination between aldehyde and ammonia is facilitated and hexamethylenetetramine is formed without previous decomposition of the formaldehyde. For this reason alone it is possible to explain the high yield up to 70%.

The construction of the reaction chamber is of the utmost importance for the reaction. It has proved most convenient to pass the gases through a reaction tube which is constricted at one point. For example, on a small scale, a tube may be pressed flat for a distance of 2 to 15 cm. to a free 90 diameter of 1 to 2 mm. and this part of the apparatus is heated. In the first place an intimate contact of the gas mixture and the walls and a uniform energetic action of the heat is secured and secondly the velocity of the gas current is increased owing 95 to the constriction of the cross section of the tube so that the time of contact of the formaldehyde with the hot walls is very small. When the tube itself serves as the contact material, an intensive contact of the gases 100 with the active material is thus obtained;

the contact material can also be introduced into the tube. The tubes can be made of various metals e. g. copper, silver, nickel-steel, iron or alloys thereof or with one another or with tin, zinc, aluminium, silicon, or of iron with a coating of one of these metals

Example.

6 volumes of methane and 12 volumes of 10 oxygen or corresponding volumes of air are mixed with 4 volumes of ammonia gas and passed through the reaction space of a copper or copper silver tube which is pressed flat for about 8 cm. normal diameter 15 mm. diameter at the constricted portion 1 to 2 mm. If the reaction is performed at low pressures (vacuum) the flat portion of the tube is heated to 500 to 700° C. but if the gases are allowed to interact at ordinary pressure 15 it is convenient not to heat higher than 300 to 500° C. The use of vacuum presents certain advantages with regard to the yield.

The reaction product is cooled in a preliminary cooler and mainly consists of hexamethylenetetramine. This is then separated 25 in known manner from impurities and can be obtained pure by crystallization. The approximate yield is 70%.

Small quantities of ammonia can also be 30 used, e. g. 6 vols. of methane, 12 vols. of oxygen and only 1 vol. of ammonia, but the yield is then poorer in hexamethylenetetramine although it is richer in pure formaldehyde; however the total yield is reduced. The process is however always 35 more advantageous if instead of pure chemically prepared methane, cheap natural gas is used. Any gas which not taking part in the reaction is led afresh to the reaction 40 tube.

The yield can be still further improved if the methane-oxygen mixture is passed through methyl or ethyl alcohol heated to about 50° C. before introduction to the 45 reaction tube. It has been found that such saturation with alcohol vapour favorably influences the course of the reaction and increases the yield. When using iron or steel tubes it is advisable to provide thin wire or 50 finely divided sheets or the like or silver, copper, tin, or alloys thereof as contact masses in the constricted part of the tube.

Instead of the reaction tube the so-called isoprene lamp can also be used in which the

gases are exposed for a short time to an intensely heated metallic wire.

It will be obvious that the dimensions of the tube and the constructed space are only given by way of illustration for small scale operations and clearly the proportions 60 must be varied in operating on the large commercial scale.

I declare that what I claim is:—

1. A process of manufacturing hexamethylenetetramine which comprises oxidizing 65 methane in presence of ammonia.

2. A process of manufacturing hexamethylenetetramine which comprises heating methane with free oxygen in presence of ammonia.

3. A process of manufacturing hexamethylenetetramine which comprises oxidizing 70 natural gas in presence of ammonia.

4. A process of manufacturing hexamethylenetetramine which comprises heating 75 methane with free oxygen in presence of ammonia and suddenly cooling the reaction-products.

5. A process of manufacturing hexamethylenetetramine which comprises heating 80 methane with free oxygen in presence of ammonia by passing the gases through a space including a heated constricted portion.

6. A process of manufacturing hexamethylenetetramine which comprises heating 85 methane with free oxygen in presence of ammonia and a metal as catalyst.

7. A process of manufacturing hexamethylenetetramine which comprises heating methane with free oxygen in presence of ammonia under reduced pressure.

8. A process of manufacturing hexamethylenetetramine which comprises heating methane associated with methyl alcohol and free oxygen in presence of ammonia.

9. A process of manufacturing hexamethylenetetramine which comprises heating methane associated with methyl alcohol vapor and free oxygen in presence of ammonia and a metal catalyst.

In witness whereof, I have hereunto signed my name this 30 day of December, 1920, in the presence of two subscribing witnesses.

HERMANN PLAUSON.

Witnesses:

VICTOR ARMSTRONG,
W. H. BURTON.
